GARMENT HANGERS

Philomene Alma De Lier, Monterey Park, Calif.

Application September 2, 1954, Serial No. 453,804

1 Claim. (Cl. 223—91)

The present invention relates to garment hangers, and particularly to a hanger adapted to hold a garment thereon against slippage. The average garment hanger includes garment supporting arms, usually held by a centrally located hook, the shoulder portions of the garment being draped over the arms. Such a construction does not at all times properly hold the garment, particularly if the hanger is supporting so-called synthetic fabrics, silks, low cut summer dresses, or evening gowns.

An object of the present invention is to provide a garment hanger so constructed and arranged as to hold a garment securely, and without damage thereto.

A further object is to provide a garment hanger wherein the garment supported by the hanger is prevented from slipping thereon.

A further object is to provide a garment hanger which is inexpensive in cost of manufacture, adaptable for the holding of many different forms of garment, and which is superior to garment hangers now known to the inventor.

In the drawing:

Figure 1 is a front elevation of the garment hanger as an entirety,

Figure 2 is a top plan view of the garment hanger shown in Figure 1,

Figure 3 is a sectional view on the line 3—3 of Figure 1, and on an enlarged scale,

Figure 4 is a fragmentary sectional view of a certain portion of the hanger, and,

Figure 5 is an enlarged fragmentary, and partially sectional view, on the line 5—5 of Figure 1.

Referring now with particularity to the drawing, the improved garment hanger includes a pair of arms 1 and 2, joined by a central enlargement 3 to which enlargement is secured a hook 4 for supporting the hanger. In the present instance, the threaded hook shank 5 is passed vertically through the enlargement 3, and secured by a nut 6. It will be observed that the shank is provided with a ring or loop 7. This permits a further hanger to be secured to the primary hanger by passing the supporting hook of the secondary hanger through the loop 7.

Each arm 1 and 2 terminates in an end depending hook, as shown at 8 and 9, the hooks facing inwardly of and below the arms of the hanger. It is preferable, although not essential, to increase the transverse width of the arms 1 and 2 to substantially ovoid in plan, as shown in Figure 2, at 10, and to curve the top surfaces at 11 (see Figure 3), so as to properly support the shoulder portions of a garment. Each arm is provided with a transverse slot 12 and 13. Joining the arms and beneath the same is a cross rod 14, and carried on the cross rod is a pair of clips 15 and 16. These clips are detailed in Figures 3 and 5, and comprise, in each instance, a pair of jaws 17 and 18, having tabs or handles 19 and 20, said jaws being hinged together at 21. This hinging is accomplished by providing as the hinge pin the cross rod 14, there being a coil spring interposed between the jaws and surrounding the cross rod, as shown at 22. Thus, the jaws 17 and 18 are urged into engagement. Preferably, each jaw has convergently tapering sides, the convergence being toward the jaw end, with

2

the inner surfaces of each jaw relieved at 23 and 24, with the outer surfaces of each jaw curved, as shown at 25 and 26, to provide sharp pointed and smooth jaw ends. As shown, the jaws 17 and 18 extend through the slots 12 and 13, the slots being of sufficient width to permit the jaws to swing apart when the tabs or handles 19 and 20 are pressed together. Furthermore, the jaw ends extend a slight distance above the top surface of each arm of the hanger.

Other features of construction of the hanger consist in providing L-shaped slots in the top surface of each arm, as shown at 27 and 28.

The operation, uses and advantages of the invention just described are as follows:

When the garment is draped upon the hanger, the handles or tabs 19 and 20 are moved to open the jaws. The lining of the garment, if it is a coat, is then positioned so as to be gripped by the jaws, preferably at a seam, in the manner shown in Figure 3. As the jaws are tapered as to width, and the jaws are so constructed and arranged as to be substantially sharp-pointed, the grip of the jaws upon the lining 29 of the garment, will be firm and will not permit the garment to slip or move on the hanger. The relieved portions 23 and 24 for the tips of the jaws allows space for receiving a portion of the lining which has been gripped. This is important where synthetic fabrics, such as Dacron, Orlon, silk and the like, are used in garment construction, as it is a notable fact that garments of this material have a tendency to slide from a hanger. The hanger may incorporate other clips, as shown in Figure 1, the clips being carried upon the cross rod 14. Ofttimes, if the garment hanger is to be used for the holding of women's wear, the straps on slips may be placed over the arms of the hanger and received within the L-shaped slots 27 and 28, as shown in Figure 4, a strap of the garment being shown at 30.

Thus, the hanger of the present invention incorporates numerous desirable features, such as the end hooks 8 and 9, which may be utilized for the hanging of various garments, and particularly garments having loops or straps. The clips, which are intermediate the clips 15 and 16, may be moved upon the cross rod 14, so as to be adjustable as to spacing for the securing of garments, and in fact, the slots 12 and 13 may be of elongated form to allow variable spacing for clips 15 and 16, to thereby assure that the main garment supported by the hanger will be maintained in a correct position, and in a position such that the garment will not be mussed.

50 I claim:

A garment hanger, including a connected pair of arms provided with suspension means, each arm being substantially ovoid in plan and provided with a vertical slot substantially positioned at the portion of greatest width of each arm, a cross rod extending beneath and between ends of said arms, a pair of clips carried by the cross rod, each clip of the pair provided with a pair of tapered sharp pointed jaws extending through the vertical slot and above each arm, and the said vertical slots being of such size as to permit opening and closing movement of the jaws.
